UNITED STATES PATENT OFFICE.

MOSES MILLER AND JACOB BLIDEN, OF BALTIMORE, MARYLAND.

GARMENT.

1,031,142.

Specification of Letters Patent.

Patented July 2, 1912.

Application filed December 12, 1911. Serial No. 665,250.

To all whom it may concern:

Be it known that we, MOSES MILLER and JACOB BLIDEN, citizens of the United States, residing at Baltimore city, State of Maryland, have invented certain new and useful Improvements in Garments, of which the following is a specification.

This invention relates to improvements in garments, and especially to nether garments which are usually supplied with waist bands. In such garments it has been usual, where separate belts are to be used, to attach a series of vertically disposed loops at intervals entirely around the waist-band through which the separate belt may be strung when desired for use and when the separate belt was not in use it was removed from the loops and stored away where it might or might not be found when again desired for use.

The object of the present invention is to provide a garment with improved means for obviating the necessity of entirely removing the belt when not in use.

A further object of the invention is to provide a garment with improved means for storing the belt on the person, out of sight when not in use.

With these and other objects in view, the invention consists in the improved garment, the construction, arrangement and combination of the parts of which will be hereinafter fully described and afterward specifically claimed.

In the accompanying drawing in which is illustrated an embodiment of the invention, Figure 1 represents a perspective view of the waist portion of a nether garment equipped with this invention, the belt being fastened at the front as when in use; Fig. 2 represents a similar view, the belt being stored away and out of use, part of the front of the waistband being broken away; and Fig. 3 represents a vertical sectional view on the plane indicated by the broken line 3—3 of Fig. 2.

Like reference characters denote the same parts in all of the figures of the drawing.

Referring specifically to the drawings 1 indicates the front and 2 the rear of a nether garment such as pants, drawers, or skirts and 3 the waistband attached to the upper edge thereof, the garment being illustrated as opening at the front, one end 4 of the waistband overlapping the other end 5 in

the usual manner and being adapted to be secured together by any ordinary means such as buttons and button holes (not shown). The waistband may be provided with the ordinary vertical belt loops 6 on the outside of the front half only, or may also be provided with such loops on the rear half also if desired, as shown at 6^a in Fig. 3.

At 7 is indicated a belt of any suitable material preferably some textile material such as canvas, or the same goods as the garment is made of, which belt is sewed or otherwise secured permanently to the upper rear edge as between the points 8 and 9, from which points to the front ends, said belt is free from the garment, one end 10 terminating at the end 5 of the waistband and the other end 11 extending beyond the overlapped ends of the waistband and overlapping the end 10, so that the ends 10 and 11 may be secured together by any suitable fasteners, as at 12, the front portions of the belt passing through the loops 6 in the usual manner.

Inside of the waistband 3 is a strip of material, as at 13, secured at its lower edge, as at 14, to the lower edge of the waistband, or it may be secured to the garment below the waistband, said strip being free at its upper edge forming an inside pocket 15 with its opening at the top edge of the waistband. The pocket may be held closed by any suitable fasteners, such as hooks and eyes or the like, as shown at 16.

When the belt is to be used it will appear as in Fig. 1, the rear half being secured at its upper edge and the ends at the front being secured as shown, but where it is desired not to use the belt, its ends 10 and 11 are removed from the loops 6, the end 11, doubled back as in Fig. 2, and the whole belt turned on its upper edge as a hinge and folded in the pocket 15, after which the pocket will be secured closed by fasteners 16, when the belt will be out of sight and its presence unsuspected, while being at hand, ready for use at any time. When the belt is stowed away in the pocket, a detached belt of leather or of textile or other material may be passed through the loops 6^a, 6, and used in the usual manner, the stored belt in nowise interfering with its use.

Slight changes or variations in the construction and location of the various parts may be made without departing from the

spirit and scope of the invention as herein-after claimed.

Having thus fully described the invention, what is claimed as new is—

- 5 1. A nether garment provided with a waistband, and a strip of material inside of the waistband of substantially the width thereof, and secured to the garment at its lower edge, forming a pocket opening 10 around the garment at the upper edge of the waistband, and a belt secured for substantially the rear half of its length at its upper edge to the upper edge of said waistband, whereby it is adapted to be folded over on 15 its upper edge into said pocket and stored therein when not in use, substantially as described.
2. The combination in a nether garment provided with a waistband, a strip of material inside of the waistband of substantially the width thereof, and secured to the garment at its lower edge, forming a pocket opening around the garment at the upper edge of the waistband, and a belt secured 20 substantially the rear half of its length at its upper edge to the upper edge of said waistband, whereby it is adapted to be folded over on 25 its upper edge into said pocket and stored therein when out of use, and fas- 30 teners secured at the upper edges of the

waistband and of the strip to secure the pocket closed, substantially as described.

3. The combination in a nether garment of the character herein described comprising a body, a waistband provided thereon, a strip of material inside of the waistband of substantially the width thereof, and secured to the garment at its lower edge, forming a pocket opening around the garment at the upper edge of said waistband, belt loops on 35 the waistband, a belt secured along its upper edge for substantially the rear half to the upper edge of the waistband, and free from the sides to the front of the garment, the ends of the belt being adapted to be passed 40 through the belt loops, one end being longer than the other and adapted to overlap the same, the said pocket so formed along the edge of the said waistband adapted to receive the belt when doubled over on its upper edge, and house it therein, and fasteners 45 for securing the said pocket closed.

In testimony whereof we affix our signatures in presence of two witnesses.

MOSES MILLER.

JACOB BLIDEN.
